(57) **CLAIM**

The ornamental design of a sink basin, as shown and described.

DESCRIPTION

FIG. 1 is a top right perspective view of a sink basin according to my new design;

FIG. 2 is a bottom right perspective view of the sink basin seen in FIG. 1;

FIG. 3 is a front view of the sink basin seen in FIG. 1; FIG. 4 is a rear view of the sink basin seen in FIG. 1; FIG. 5 is a right side view of the sink basin seen in FIG. 1, the left side view being a mirror image thereof;

FIG. 6 is a top plan view of the sink basin seen in FIG. 1; FIG. 7 is a bottom plan view of the sink basin seen in FIG. 1;

FIG. 8 is a top right perspective view of another embodiment of a sink basin according to my new design;

FIG. 9 is a bottom right perspective view of the sink basin seen in FIG. 8;

FIG. 10 is a front view of the sink basin seen in FIG. 8; FIG. 11 is a rear view of the sink basin seen in FIG. 8; FIG. 12 is a right side view of the sink basin seen in FIG. 8, the left side view being a mirror image thereof;

FIG. 13 is a top plan view of the sink basin seen in FIG. 8; and,

FIG. 14 is a bottom plan view of the sink basin seen in FIG. 8.

In FIGS. 8-14, the sink basin is shown with a symbolic break in its length. The appearance of any portion of the article between the break lines forms no part of the claimed design. In the drawings, the broken lines depict environmental subject matter only and form no part of the claimed design. Shade lines in the figures are a combination of long and short lines and show surface contour, not surface ornamentation.
